UNITED STATES PATENT OFFICE

GEORGE R. KNEESHAW, OF NILES, MICHIGAN, ASSIGNOR TO THE KAWNEER COMPANY,
OF NILES, MICHIGAN, A CORPORATION OF MICHIGAN

STORE FRONT CONSTRUCTION

Application filed September 28, 1931. Serial No. 565,408.

The present invention relates to store front constructions and more in particular to a novel cap construction adapted to overlie or abut the adjacent ends of the sash members.

5 Among the objects of the invention is to provide a novel cap construction for covering or connecting the ends of adjacent sash members, these sash members mounting and retaining the adjacent panes of glass in position.

10 A further object is the provision of a novel cap construction and means for mounting and retaining the same in a position whereby to cover or connect the ends of the sash moldings.

15 Another object of the invention is the provision of a novel retaining means for a cap member whereby to permit accurate and ready mounting and positioning of the cap member with the adjacent ends of the sash members. The invention comprehends the provision of a sectional cap construction in which one of the members is provided with a projection and the other with means for receiving and retaining said projection whereby to hold the cap member in predetermined mounted position.

20 A still further object of the invention is the provision of a sectional cap construction adapted to be readily attached or detached and/or replaced with a minimum of effort.

25 Further objects are to provide a construction of maximum simplicity, efficiency, economy and ease of assembly and operation and such further objects, advantages and capabilities as will more fully appear and as are inherently possessed thereby.

30 The invention further resides in the combination, construction and arrangements of parts illustrated in the accompanying drawings and while there is shown therein a preferred embodiment it is to be understood that the same is susceptible of modification and change and comprehends other details and constructions without departing from the spirit of the invention.

In the drawings:

35 Fig. 1 is a fragmentary view in perspective of a store front construction provided with 40 the novel cap arrangement.

Fig. 2 is a view in horizontal cross section through the corner cap construction, taken on the line 2—2 of Fig. 3.

Fig. 3 is a fragmentary view in vertical cross section through the construction disclosed in Fig. 2. 55

Fig. 4 is a disassembled view in perspective of the sectional cap construction.

Fig. 5 is a view in perspective disclosing a cap for a reverse construction. 60

Fig. 6 is a view similar to Fig. 4 of another form of cap construction.

Fig. 7 is a cross sectional view similar to Fig. 2 but disclosing the sash members and cap in abutting relation. 65

Fig. 8 is a view in front elevation of a mirror showing another embodiment of the invention.

Referring more in detail to the construction disclosed in the drawings in connection with a window or store front construction, which however is but one embodiment of the invention, the sash construction comprises outer molding members 1 and inner members 2 which are adapted to be mounted upon a sill or base A, the outer molding being provided with glass engaging portion 3 while the inner molding is provided with glass engaging portion 4, these portions being adapted to seat against the glass and retain the same in adjusted position. In order to sustain the weight of the panes of glass 5 the sash members are provided with setting blocks 6 having a face or cushion 7 of leather or the like with which the lower edge of the glass is in contact. 75

80 The present invention comprehends a novel cap construction which comprises an outer section or cap member 8 and an inner section or bracket 9, the former having in the present instance, the same general contour as the outer molding or sash members 1 and adapted to conformably seat thereon or thereagainst, and provided with a rearwardly extending tongue or projection 10 adapted to tensionally seat within spaced spring flanges or lips 11 formed on the inner section or bracket 9. 85 The tongue or projection 10 is serrated and is adapted to be received intermediate the flanges or lips 11 which are serrated on their 90

inner surface to suitably engage and retain the tongue or projection. The rear section or bracket 9 is provided with outwardly extending ears 12 having openings 13 there-
5 in whereby these ears may be suitably attached to the floor or the gutter of the sash members so as to mount and retain the bracket member.

In Fig. 5 is disclosed a construction for a
10 reverse corner in which the cap member 8^a is formed at a reverse angle to that disclosed in Fig. 2 and provided with a tongue or projection 10^a. In this construction, the sides
15 16 of the cap member 8^a may overlie the sash members, or these side members may merely abut thereagainst, as for example, where the sash members are of heavy or extruded metal. The reverse bar construction 14 and the corner bar construction 15 disclosed in Fig. 1
20 may be of any suitable design for retaining adjacent panes of glass.

In Fig. 6 is disclosed another embodiment of the invention in which the cap member 18 is provided with sides 19 adapted to overlie
25 or abut, and connect the sash members 1 and 1^a, the latter providing retaining means for a vertical edge of the glass 5, as more particularly disclosed in Fig. 1. In this form as in the other embodiments, the cap is provided with a serrated tongue or projection 20 adapted to be received between spaced serrated lips or flanges 21 on the bracket or retaining lug 22. Ears 23 permit this bracket or retaining lug to be attached to the gutter
30 or floor of the sash members. This form is adapted to connect or join the adjacent sash sections whether they be mitered, in which case the cap will overlie the sash members, or whether they be made to merely abut the
35 40 edges or ends of the cap member.

Fig. 7 discloses a construction similar to Fig. 2, but in which the ends of the sash members 1 and of the sides 24 of the cap member 25 abut. This embodiment is particularly
45 adapted for use with heavy or extruded sash members.

Although the preceding disclosure refers more particularly to the employment of the cap member with sash constructions, the invention is likewise admirably adapted for use in various mirror or window constructions, as shown in Fig. 8. In this form, the sides or frame members 26 and 27 of the mirror or window are disclosed as mitered,
50 55 the cap member 28 being positioned to overlie or abut the ends of the frame members. The tongue or projection 29 passes between these frame members and is adapted to be attached by means of a bracket or lug, similar in construction to that shown in Fig. 6. This invention is also adapted for door constructions or panel constructions of various kinds, in fact, wherever moldings, sash or
60 65 frame members are employed for retaining

panes of glass or panels of various forms and descriptions.

By reason of the present construction and arrangement, the invention comprehends a snap-on cap which may be readily applied and assembled as well as disassembled. Whether the cap member is for a corner, division or reverse construction the details would be the same except for the angle of the cap members so that the construction has a
75 universal application.

Having thus disclosed the invention, I claim:

1. In a store front construction provided with sash members for retaining adjacent panes of glass, a cap member adapted to connect the ends of adjacent sash members, said cap member being provided with a tongue adapted to project intermediate the sections of glass, and spaced members for frictionally engaging said tongue therebetween for retaining said cap member in position.

2. In a store front construction provided with sash members for mounting and retaining panes of glass, a cap construction for connecting the ends of the adjacent sash members, said construction comprising a cap adapted to overlie the ends of the outer sash members, a projection on said cap, and spaced members adapted to interengage with said projection for retaining the cap in position.

3. A cap construction for joining the ends of the adjacent frame members, said construction comprising a cap adapted to join the ends of the frame members, a projection on said cap, a bracket member, and spaced lips on said bracket member for receiving and frictionally engaging said projection for retaining the cap in position.

4. A cap construction for connecting the ends of the adjacent frame members, said construction comprising a cap adapted to join the ends of the frame members, a bracket member, and spaced members on said bracket member adapted to interengage with a part on said cap for retaining the cap in position.

5. In a store front construction provided with sash members for mounting panes of glass, and a cap construction for joining the adjacent ends of the sash members, said cap construction comprising a cap section adapted to abut the ends of the sash members and provided with a projection and a retaining section adapted to frictionally engage the projection of said cap section for retaining the cap in position.

6. A cap construction for connecting the adjoining ends of the frame members, said cap construction comprising a cap section adapted to join the ends of the frame members, a tongue on said section, and a retaining section provided with spaced lips adapted to receive and retain the tongue therebetween.

7. A cap construction for connecting the adjoining ends of frame members, said cap

construction comprising a cap section adapted to connect the ends of the frame members, a tongue on said section, and a retaining section provided with spaced lips adapted to receive and retain the tongue therebetween, said tongue and lips being formed with serrations whereby to provide gripping surfaces.

5 8. A cap construction for connecting the ends of frame members, said cap construction comprising a cap member provided with a rearwardly extending projection and a bracket member provided with spaced flanges for receiving and retaining said projection whereby to retain the cap member in position.

10 9. A cap construction for connecting the ends of frame members, said cap construction comprising a cap member provided with a rearwardly extending projection and a bracket member provided with spaced flanges for receiving and retaining said projection whereby to retain the cap member in position, the contacting portions of said projection and flanges being serrated.

15 10. A cap construction for joining the ends of adjacent frame members, said construction comprising a cap member and a retaining member, and spaced lips on one of said members for receiving and frictionally engaging a projection on the other of said members

20 whereby to retain the cap member in position.

25 11. A cap construction for connecting the adjoining ends of frame members, comprising a cap section and a retaining section, spaced lips on one of said sections and a tongue on the other of said sections adapted to be received and retained intermediate said lips whereby to retain the cap section in adjusted position.

30 In witness whereof, I hereunto subscribe
35 my name to this specification.

GEORGE R. KNEESHAW.
